E. W. Bullinger

UNITED STATES PATENT OFFICE.

E. W. BULLINGER, OF NEW YORK, N. Y.

IMPROVEMENT IN GAS STOVES.

Specification forming part of Letters Patent No. 42,071, dated March 29, 1864.

To all whom it may concern:

Be it known that I, E. W. BULLINGER, of the city, county, and State of New York, have invented a new and Improved Gas Heating and Cooking Apparatus; and I do hereby declare that the following is a full, clear, and exact description of the same, reference being had to the accompanying drawings, forming part of this specification, in which—

Figure 1 represents a plan or top view of my burner. Fig. 2 is a vertical central section of the whole apparatus, showing its operation. Fig. 3 is a modification of the same. Fig. 4 is a plan or top view of the socket and platform which supports the burner.

Similar letters in the several views refer to corresponding parts.

The object of this invention is to produce the largest possible heat by the consumption of the least possible quantity of gas.

To enable those skilled in the art to make and use my invention, I will proceed to describe it.

A represents a cylinder or inverted truncated cone, open at both ends and inclosing one or more cylinders, B, which are also open at both ends, and which are so proportioned in relation to the outer cylinder that an annular chamber, C, is formed in which the gas mixes with atmospheric air. The top end of the outer cylinder may be formed with a shoulder and projecting edge, or there may be over the top of it a cap, D, fitting over a shoulder, a, on the top edge of the said cylinder. This cap has a projecting edge, b, either straight, oblique, or curved upward, as may be desired. The inner cylinder, B, may be of the same length as the outer one and cap combined, so as to bring its upper edge on a level with the upper edge of the cap, or it may be somewhat longer or shorter, as may be found advantageous, or it may be of the same length as the outer cylinder, and have fitted over the top of it a cap, E, of any height, with an edge, c, either straight, oblique, or curved.

Between the two cylinders is placed a piece of perforated metal, F, held in place by its

outside edge or circumference being clamped between the cap D and upper edge or shoulder, a, of the outer cylinder, and if found necessary by similar means on the inner cylinder. This perforated metal disk acts as a stay or brace to hold the two cylinders in position and also prevents the flame from falling below and igniting the gas in the mixing-chamber, or at the perforations in the gas tube or conductor.

The cylinder may be held steady below by a piece or pieces of wire being thrust laterally through them, or they may be fitted over or inside of flanges d e, rising for that purpose from the bottom plate G. (See Figs. 2 and 4.)

H is the pipe which conducts the gas to the burner, and this pipe is provided with two oblique perforations, f, which throw the gas in an upward inclined direction into the chamber C. This chamber being open at the bottom admits a current of atmospheric air, which freely mixes with the gas, the operation of mixing being considerably facilitated by the oblique direction of the gas-jets f. The mixture of gas and air thus obtained is ignited and it burns between the edges b and c of the caps D E. Into the flame thus formed a supply of fresh air is conducted through the central air passage or passages, B, and, if the gas has sufficient pressure, the flame forms an annular cone, as shown in Figs. 2 and 3, and not a particle of gas is allowed to escape without coming in contact with a sufficient quantity of atmospheric air to consume it. By these means a great economy in gas is effected and an apparatus is obtained which can be used with considerable advantage for heating or cooking purposes.

What I claim as new, and desire to secure by Letters Patent, is—

The combination of the edges b c with an annular gas-making chamber, C, and its disk F, substantially as herein shown and described.

E. W. BULLINGER.
